CLAIM

The ornamental design for a wrap panel for a shelf rack, as shown and described.

DESCRIPTION

FIG. 1 is a top plan view of a wrap panel for a shelf rack showing my claimed design in a flat configuration and not in use, the bottom plan view being a mirror image thereof; FIG. 2 is a top plan view of FIG. 1 with portions shown separated along the perforation edges from the remainder of the panel, the bottom plan view being a mirror image thereof;

FIG. 3 is a front left top perspective view of the panel of FIG. 1 shown in a folded configuration and in use with a shelf rack shown in dashed lines;

FIG. 4 is a front elevation view of FIG. 3;

FIG. 5 is a rear elevation view of FIG. 3;

FIG. 6 is a top plan view of FIG. 3, the bottom plan view being a mirror image thereof;

FIG. 7 is a left side elevation view of FIG. 3; and,

FIG. 8 is a right side elevation view of FIG. 3.

The dotted lines indicating perforated edges in FIG. 1 form part of the claimed design.

The broken lines showing in FIGS. 3, 5, 6, 7, and 8 are for the purposes of illustrating the environment of the article only and form no part of the claimed design.
